Patented Feb. 6, 1917.

UNITED STATES PATENT OFFICE.

WILLARD D. RICHARDSON, OF COLUMBUS, OHIO.

WALL STRUCTURE.

1,214,826.

Specification of Letters Patent.

Patented Feb. 6, 1917.

Application filed December 21, 1914. Serial No. 878,258.

To all whom it may concern:

Be it known that I, WILLARD D. RICHARDSON, a citizen of the United States, residing at Columbus, in the county of Franklin and State of Ohio, have invented certain new and useful Improvements in Wall Structures, of which the following is a specification.

My invention relates to wall structures and it has for its principal object the provision of such structure whereby a thin brick veneer may be practically applied to an ordinary backing or burden bearing wall, thus giving to such wall an impervious facing of any desired color or texture. In this connection, my structure also is such that the finished wall will have the appearance of a solid structure of the ordinary standard sized brick now in use, the thickness of this brick being approximately two and three-eighths inches and its length approximately eight and one-fourth inches. However, my facing brick is of such width that its weight as compared to a standard brick is materially reduced, which naturally reduces its cost of manufacture and its cost of shipment.

Specifically stated, my invention has for its object the provision of a plurality of burden bearing units and a plurality of facing units, each being provided with coöperating dove tail projections extending outwardly centrally from one of their faces in a direction at right angles to their thickness dimensions.

A further object of my invention resides in so constructing my wall that there are no continuous joints to the same from exterior to interior, the brick veneer overlapping the joints of the common or burden bearing units, thus making the thinnest practical wall strictly impervious to moisture.

The preferred embodiment of my invention is shown in the accompanying sheet of drawings, in which similar characters of reference designate corresponding parts, and in which:

Figure 1 shows a section of a wall in end view with my facing units supplied, Fig. 2 is a view in perspective of a wall constructed in accordance with my invention, Fig. 3 is a view in perspective of one of the facing units, Fig. 4 is a view in perspective of one of the burden bearing units, and, Fig. 5 is a view similar in nature to Fig. 1, but showing

the veneer applied to both the interior and exterior faces of the burden bearing units.

In these views, the facing unit or brick is designated generally by the reference numeral 1, and is shown as being provided on its rear face with a centrally disposed rearwardly projecting tongue 2 of dove-tail nature, in that its extreme rear portion is of greater thickness than its connecting or neck portion 3. These dove-tail projections are preferably centrally disposed have all of their longitudinal corners rounded and are of considerably less thickness than the thickness of the facing unit as a whole, in order that they may coöperate with similar dove-tail projections 4 also centrally disposed and extending forwardly in a direction at right angles to the thickness of each of the burden bearing units 5. These burden bearing units 5 may be provided with a single dove-tail projection, as shown in Fig. 1, or they may be provided on both their rear and forward faces with these projections, as shown in Fig. 5. For purposes of lessening the weight of the burden bearing units, I have provided each with a plurality of apertures 6 located as may be desired to accomplish the result sought. In order that these facings may be made without cracks and also have a flat surface to lie on when being burnt, I have made the front face of each, the rear face from which the dove-tail formations project and the rear face of these formations flat and in parallel planes.

From the foregoing description, it will appear that the formation 2 upon each of the facing units is similar to the formation 4 upon each of the burden bearing units and, since these projections are centrally disposed as regards the thickness of each, it follows that if they are arranged to coöperate to securely bond to each other, a wall will be provided wherein there are no continuous joints through the same from exterior to interior as regards horizontal mortar joints and by the well known staggered arrangement of vertical joints of the two units, no continuous joints will appear in this direction, the brick veneer in each case overlapping the joints of the burden bearing units. It must, therefore, be apparent that I have provided a type of structure wherein a wall may be provided having all the appearances of an ordinary brick construction and having corresponding properties as re-

gards strength. This construction may be had in a very efficient manner and at a greatly reduced cost, the peculiar nature of the dove-tail projections insuring a perfect and lasting bond between the facing and burden bearing units.

What I claim, is:

A wall structure having a relatively thin facing veneer and made up of a plurality of 10 superimposed backing units of such thickness as to extend through and form the burden bearing portion of the wall and of the height and length of a standard brick and having parallel upper and lower faces, each 15 of said units having a longitudinally extending, centrally disposed dovetail rib formed along its front face, the facing veneer comprising thin slabs of facing material of the length and height of a standard

brick and having longitudinally extending 20 dovetail ribs centrally disposed upon their rear faces, whereby when the dovetail ribs of the facing slabs are disposed between the dovetail ribs of the superimposed backing units said slabs overlie the joints between 25 the said units to prevent the formation of a mortar joint completely through the wall, said slabs being so disposed longitudinally of the backing units that the vertical joints between the slabs lie out of alinement with 30 the vertical joints between the backing units.

In testimony whereof I affix my signature in presence of two witnesses.

WILLARD D. RICHARDSON.
